UNITED STATES PATENT OFFICE

HARRY W. THATCHER, OF HOPEDALE, MASSACHUSETTS, ASSIGNOR TO DRAPER CORPORATION, OF HOPEDALE, MASSACHUSETTS, A CORPORATION OF MAINE

SHUTTLE BOX MOTION FOR LOOMS

Application filed February 8, 1930. Serial No. 426,802.

This invention relates to a shuttle box motion for a shifting shuttle box loom and its object is to provide a simple and efficient form of mechanism for shifting the boxes at regular intervals or at such predetermined times as may be required under the control of a dobby or other pattern mechanism.

The object of the invention is further to provide such a mechanism which shall be readily adjustable to assemble the parts in proper position, or whenever required, to time the movement of the boxes in proper relation with the other mechanisms of the loom.

The object of the invention is further to provide means for giving a variable speed to the shifting movement of the boxes as may be required.

The object of the invention is further to provide means for giving such a variable speed to enable the box shifting motion to have a slow movement both when the gears which determine the shifting movement engage and disengage.

The object of the invention is further to provide means for adjusting the connections imparting shifting movement to the boxes so as to vary the effect thereof without materially altering their position.

These and other objects and features of the invention will appear more fully from the accompanying description and drawings and will be particularly pointed out in the claims.

In its preferred form, the mechanism in which this invention is embodied is largely self-contained and may be readily attached to or embodied in existing looms. The drive for the mechanism is obtained from one of the regular shafts of the loom such, for example, as the shaft from which the shuttle picking motion is operated. Consequently it is only necessary here to illustrate and describe those parts of a loom with which the invention is particularly concerned.

The drawings disclose a portion of a side frame of a loom, the pick motion shaft, and a portion of an ordinary form of shifting shuttle box structure, together with a preferred form of the invention embodied therein.

Fig. 1 is a side elevation of the construction.

Fig. 2 is a top plan view partially in horizontal cross section.

Fig. 3 is a left-hand end elevation of a portion of the mechanism.

A portion of one of the side frames 1 of a loom is shown with the end of the shaft 2 employed to operate the picking motion journaled in this side frame. The shifting shuttle box structure is shown as comprising the shuttle boxes 3 supported on the end of a lifter rod 4 mounted to slide longitudinally in the lay, not shown, and having a stud 5 engaging the giveaway link connection 6 of a familiar type adjustably pivoted at 7 to a horizontally disposed lever 8. Thus, in a manner generally well known and familiar in the art, the shuttle box structure is raised and lowered to bring one or the other of the boxes into working position, as required, by the movement of the lever 8. The invention, in its preferred form, has to do with the means for operating this lever and also with the means for adjusting the effective throw of this lever.

In the preferred construction illustrated, a bracket 9 comprising a generally flat plate is rigidly secured to the side frame 1 of the loom on the outside thereof and in parallelism therewith. For this purpose the bracket 9 is provided with separating sleeves 10 extending between it and the side frame 1 through which bolts 11 are passed and which rigidly secure the bracket to the side frame.

The bracket 9 is provided with a bearing hub 12 in which is journaled, parallel to the driving shaft 2, an auxiliary shaft. This auxiliary shaft is shown as having three integral sections, the section 13 of intermediate diameter being journaled in the hub 12, the section 14 of smallest diameter extending toward the frame, and the section 15 of largest diameter extending outward.

Means are provided for driving the auxiliary shaft from the driving shaft 2 which are adjustable to shift the relative rotary positions of said shafts and thus enable the box shifting motion to be assembled or at any time to be adjusted so as properly to time the shift of the boxes with respect to the pick motion or other mechanism of the loom.

and without disturbing in any way the box shifting mechanism itself. Preferably also means are provided for thus driving the auxiliary shaft from the driving shaft which will enable the speed of the auxiliary shaft to vary with respect to the constant speed of the driving shaft and thus enable, for example, the shifting mechanism to operate at a slow speed when the shifting gears are engaging and disengaging or which enable the speed to be changed for any other reason desired.

Any suitable means for carrying out these purposes may be provided for thus transmitting the motion from the shaft 2 to the auxiliary shaft, preferably, however, a train or system of gears, and for that purpose a pair of meshing eccentric gears is illustrated, one on each shaft, and one of which is rotarily adjustable with respect to the shaft upon which it is mounted. For that purpose there is shown an eccentric gear 16 secured to and rotatably adjustable on the shaft 2 by means of the set screws 17 and a cooperating eccentric gear 18 keyed at 19 to the section 14 of the auxiliary shaft.

The mechanism for transmitting motion from the auxiliary shaft to the lever 8 by which the boxes are shifted as required is of a generally old type of construction. A mutilated gear 20 is journalled on a shaft 21 mounted in the bracket 9 and extending outwardly therefrom in parallelism with the auxiliary shaft. This mutilated gear has a hub 22 provided with positioning recesses into which a roller 23 carried by a detent arm 24 is pressed each time a shifting movement is completed. This detent arm is shown as having a hub 25 journalled on a stud 26 projecting outwardly from the bracket and is controlled by a spring 27 on the hub.

A longitudinally adjustable link 28 is journalled at its upper end on the stud 29 secured in a crank arm 30 rotating with the gear 20 and at its lower end is pivoted at 31 to the lever 8.

It will thus be seen that with each half rotation of the gear 20 the lever 8 is rocked and the boxes shifted up or down. Various adjustments are provided for controlling the position and the extent of movement of the boxes. The link 28 is itself adjustable lengthwise by means of a turnbuckle construction 32, the lifter rod 4 is adjustable in the box structure at 33, the lower end of the give-way link 6 has its pin 7 longitudinally adjustable in the slide 34 of the lever 8. But a novel adjustment is here provided for the fulcrum of the lever 8 which enables this fulcrum to be adjusted so as to vary the lever-age ratio without changing the position of the lever.

In the construction illustrated, a bracket 35 is secured to the loom side 1 by bolts 36 and projects outwardly therefrom. A bearing stud is adjustably mounted in this

bracket. This bearing stud comprises a shouldered sleeve 37 having its larger end abutting the outer face of the bracket 35 which is slotted horizontally at 38 and further comprises a bolt 39 passing through the sleeve with its head 40 on the inside of the bracket and with the nut 41 abutting a washer 42 resting against the outer end of the sleeve 37. Thus it will be seen that the bearing stud may be adjusted by means of the bolt 39 in a general horizontal direction and longitudinally of the lever in the bracket 35. The lever 8 is provided with a fulcrum hub 43. This hub is journalled on the smaller section of the sleeve 37 of the bearing stud and is adjustable longitudinally of the lever by means of the bolts 44 passing through slots both in the fulcrum hub and in the lever while a slot 45 in the lever enables the bearing stud to move with the hub without moving the lever. Thus it will be seen that the fulcrum point of the lever is adjustable both longitudinally of, and with respect to, the lever and that consequently the effect of the lever in the shifting of the shuttle box structure may be varied without shifting the position of the lever.

The mutilated gear 20 is given a half rotation each time a shift of the box is to take place by the rotation of a sector gear 46 keyed at 47 to the section 15 of the auxiliary shaft. This sector gear is shifted into and out of the plane of, and thus into and out of mesh with, the gear 20, as required, by any usual suitable mechanism. In the form illustrated, the gear 46 is provided with a grooved hub 48, the groove of which is engaged by a forked arm 49 secured by the set screws 50 to a shaft 51 journalled in lugs 52 projecting outward from the bracket 9. An arm 53 is secured by set screws 54 to the shaft 51 and projects inwardly therefrom. This arm 53 is shown as operated by a rod 55 extending upwardly therefrom to a dobby or other suitable pattern mechanism. A set screw 56 adjustably mounted in the arm 53 abuts against the bracket 9 to limit the outward throw of the sector gear 46 and a spring 57 coiled on the shaft 51 and engaging at one end the lug 52 and at the other end a collar 58 on the shaft acts normally to move the sector gear 46 inward or to meshing position.

If the gears 46 and 20 are left in mesh, as shown, the shift of the shuttle box structure will take place regularly at each rotation of the auxiliary shaft. The sector gear 46 is also shifted under the control of a dobby or other mechanism through the rod 55 and this shift will take place as determined thereby, all in the well-known and familiar manner.

It will thus be seen that there is provided a simple and effective mechanism for securing the shift of the shuttle boxes which can be readily assembled or readily adjusted at any time so as to provide a proper relation

between the movement of the shuttle boxes and the pick motion or other mechanism of the loom, that the speed of the shifting movement may be varied as desired, and that the 5 lever through which the shifting movement is transmitted may be adjusted so as to adjust the shifting movement without altering the position of the lever.

Having thus described the invention, what 10 is claimed as new, and desired to be secured by Letters Patent, is:

1. In a loom, a shiftable shuttle box structure, a pair of gears having parallel axes and one of which is shiftable on its axis into 15 and out of mesh with the other, means including a lever connecting one of said gears to the shuttle box structure to impart shifting motion thereto, means for rotating the other gear, and means for adjusting the ful- 20 crum of the said lever both longitudinally of and with respect to the lever thus to vary the effect of the lever in transmitting movement to the shuttle box structure without altering the position of the lever.

2. In a loom, a shiftable shuttle box structure, a pair of gears having parallel axes and one of which is shiftable on its axis into and out of mesh with the other, means including a lever connecting one of said gears 30 to the shuttle box structure to impart shifting motion thereto, means for rotating the other gear, a fulcrum hub secured to and adjustable longitudinally of said lever and a bearing stud for the hub secured to the 35 loom and adjustable thereon longitudinally of the lever thus to permit the effect of the lever in transmitting the shifting movement to be varied without altering the position of the lever.

3. In a loom, a shiftable shuttle box structure, a bracket rigidly secured to the loom side in parallelism therewith, a driving shaft having a bearing in the loom side and projecting therethrough, an auxiliary shaft having 45 a bearing in the bracket and projecting at both sides thereof, a pair of intermeshing gears between the side frame and the bracket mounted respectively on the said shafts, means for adjusting one of the said gears 50 rotarily with respect to the shaft on which it is mounted, a gear non-rotatably mounted on the auxiliary shaft outside the bracket, a gear journalled on the outside of the bracket and adapted to mesh with the preceding 55 gear, means for shifting one of said latter two gears on its axis into and out of mesh with the other, and means connecting the gear journalled on the outside of said bracket to the shuttle box structure to impart shifting 60 motion thereto.

4. In a loom, a shiftable shuttle box structure, a bracket rigidly secured to the loom side in parallelism therewith, a driving shaft having a bearing in the loom side and projecting therethrough, an auxiliary shaft hav-

ing a bearing in the bracket and projecting at both sides thereof, a pair of variable speed intermeshing gears between the side frame and the bracket mounted respectively on the said shafts, means for adjusting one of the 70 said gears rotarily with respect to the shaft on which it is mounted, a gear non-rotatably mounted on the auxiliary shaft outside the bracket, a gear journalled on the outside of the bracket and adapted to mesh with the preceding gear, means for shifting one of said latter two gears on its axis into and out of mesh with the other, and means connecting the gear journalled on the outside of said bracket to the shuttle box structure to im- 75 part shifting motion thereto.

5. In a loom, a shiftable shuttle box structure, a bracket rigidly secured to the loom side in parallelism therewith, a driving shaft having a bearing in the loom side and projecting therethrough, an auxiliary shaft having a bearing in the bracket and projecting at both sides thereof, a pair of intermeshing gears between the side frame and the bracket mounted respectively on the said shafts, 80 means for adjusting one of the said gears rotarily with respect to the shaft on which it is mounted, a sector gear keyed to the auxiliary shaft on the outside of the bracket, a mutilated gear journalled on the bracket and adapted to mesh with the sector gear, means connecting the mutilated gear to the shuttle box structure to impart shifting motion thereto, and means for shifting the sector gear on the auxiliary shaft into and out of 85 mesh with the mutilated gear.

In testimony whereof, I have signed my name to this specification.

HARRY W. THATCHER.
